(57) **CLAIM**

The ornamental design for a zip tie wall mount, as shown and described.

DESCRIPTION

FIG. 1 is a top-to-bottom view of a wall mount.

FIG. 2 is a bottom-to-top view of a wall mount.

FIG. 3 is a side view of a wall mount, the space within the dashed lines representing hollow areas within the wall mount, the left and right sides being mirror images of each other.

FIG. 4 is a front view of a wall mount, the space within the dashed lines representing hollow areas within the wall mount, the front and back being mirror images of each other.

FIG. 5 is an environmental perspective view from above a wall mount, the dashed line representing a zip tie or other rope-, string-, or strap-like fastener threaded through the wall mount.

FIG. 6 is an environmental side view of a wall mount, the dashed line representing a zip tie or other rope-, string-, or strap-like fastener threaded through the wall mount; and,

FIG. 7 is an environmental top view of a wall mount, the dashed line representing a zip tie or other rope-, string-, or strap-like fastener threaded through the wall mount.

The zip tie wall mount is characterized by a block-like head on a threaded shaft. The top face of the head has an aperture of an approximate size and shape as necessary to accommodate the tip of a driver head. Another aperture runs longitudinally from the front face to the back face of the head.

The broken line showing of the rope, string or strap is included for the purpose of illustrating environment and forms no part of the claimed design.
